UNITED STATES PATENT OFFICE.

MARION L. NICHOLS, OF NEWARK, NEW JERSEY, ASSIGNOR TO THE EVOLUTION CYCLE COMPANY, OF WASHINGTON, DISTRICT OF COLUMBIA.

DESIGN FOR A CASING OR BRACKET FOR BICYCLES.

SPECIFICATION forming part of Design No. 28,352, dated March 8, 1898.

Application filed August 3, 1896. Serial No. 601,574. Term of patent 7 years.

To all whom it may concern:

Be it known that I, MARION L. NICHOLS, a citizen of the United States, residing at Newark, in the county of Essex and State of New Jersey, have invented and produced a new and original Design for a Bicycle Casing or Bracket, of which the following is a specification, reference being had to the accompanying drawings.

Figure 1 is a side elevation of a center bracket or gear-casing for bicycles. Fig. 2 is a plan or top view of the same.

The leading feature of my design consists of a bracket in substantially circular form in side elevation, with sockets extending out therefrom to receive the frame-sections, part of which extend centrally from the periphery of the rim, while the others extend rearward from the side faces of the casing.

A represents the center of the case or

bracket in substantially circular form in general contour in side elevation, the lower part A' being divided from the upper part to form a detachable lid or cover. Extending from the upper portion of the case centrally of the 25 peripheral face are sockets B B, while extending rearwardly on each side of the case are sockets C C. Formed in the center of the case are hubs D for the ball-cases of the pedal-shaft, the whole being cast integral. 30

What I claim is—

The design for a center bracket for bicycles, substantially as herein shown and described.

In testimony whereof I affix my signature 35 in presence of two witnesses.

MARION L. NICHOLS.
